PALATE SUPPORT FOR SMOKERS' PIPES

John C. Casey, San Francisco, Calif.

Application June 8, 1951, Serial No. 230,655

2 Claims. (Cl. 131—228)

1

This invention relates to improvements in a palate support for smokers' pipes.

The principal object of this invention is to provide means for attaching to a smoker's pipe a supporting element which will contact the roof of the mouth so as to act as a support for the pipe, thus relieving the necessity of biting the stem between the teeth and to relieve some of the jaw tension thereby.

A further object is to produce a device of this character which may be readily attached to any ordinary pipe.

A further object is to produce a device of this character which is economical to manufacture, one which may be readily withdrawn from the pipe for cleaning purposes and a device which will not injure the mouth.

Other objects and advantages will be apparent during the course of the following description.

In the accompanying drawings forming a part of this specification and in which like numbers are employed to designate like parts throughout the same,

Fig. 1 is a top plan view of my device on an enlarged scale;

Fig. 2 is a cross-sectional view taken on the line 2—2 of Fig. 1;

Fig. 3 is a cross-sectional view taken on the line 3—3 of Fig. 1;

Fig. 4 is a fragmentary view of a modified form of my device; and

Fig. 5 is a perspective view on a reduced scale, showing my device in use in a pipe.

The ordinary pipe used by a smoker consists of a stem, together with a bowl, both of which project a considerable distance out of the mouth and therefore there is an appreciable leverage between the teeth which tends to push the lower jaw inwardly, and, consequently, considerable muscular effort must be exerted in order to keep the pipe in a substantially horizontal position.

Applicant has devised a palate support which projects backwardly into the mouth a sufficient distance to counteract the leverage so that the lower jaw merely has to support the weight of the pipe, which is comparatively small.

In the accompanying drawings, wherein for the purpose of illustration is shown a preferred embodiment of my invention, the numeral 5 designates a stem engaging portion having downwardly struck resilient tongues 6 and 7 and a palate engaging grooved, flared portion 8.

With this construction it is possible to push the stem-engaging portion into the bore 9 of a pipe stem, as shown at 11. The two downwardly extending tongues have their lower ends biting into the bottom of the bore, thus preventing withdrawal of the device. However, when it is desired to withdraw the device, the stem may be removed from the bowl and a pipe cleaner

2

pushed in against the tongues, thus loosening them from the bottom of the bore.

In the modified form shown in Fig. 4, the stem engaging portion is shown at 12 and is provided with screw threads so that it may be secured into a pipe or removed therefrom as desired. This threaded portion is split so as to provide resilient portions 13 and 14, the purpose of which is obvious.

10 It is to be understood that the form of my invention herewith shown and described is to be taken as a preferred example of the same and that various changes relative to the material, size, shape and arrangement of parts may be resorted to without departing from the spirit of the invention or the scope of the subjoined claims.

Having thus described my invention, I claim:

1. A palate support for smokers' pipes, comprising a stem engaging portion having spaced resilient members connected thereto, and bearing against the opposite side of the bore of the pipe from that engaged by the stem-engaging portion having a semicircular cross section conforming to the interior of the pipe bore, and a flared palate-engaging portion rigidly secured to said stem-engaging portion said palate engaging portion being bent upwardly and having an upwardly convex surface for area bearing contact with the palate of the user.

2. A palate support for a smoker's pipe comprising a stem-engaging portion, having a semicircular cross section, conforming to the interior wall of pipe bore for bearing against a portion of the bore of a pipe, said stem-engaging portion having resilient members connected thereto and bearing against the opposite side of the bore of the pipe from the curved portion, said resilient members extending rearwardly toward the free end of the stem and a curved upwardly flared palate-engaging portion having an upwardly convex palate-engaging surface rigidly secured to said stem-engaging portion.

JOHN C. CASEY.
